APPARATUS FOR ESTABLISHING A STANDARD CRANIAL POINT OF ORIENTATION OF LIVING PERSONS

Edgar W. Snell, San Francisco, Calif.

Application October 12, 1953, Serial No. 385,425

3 Claims. (Cl. 33—174)

An object of my invention is to provide an improvement on my patent for an apparatus for establishing a standard cranial point of orientation of living persons, Patent No. 2,101,105, issued December 7, 1937. In the patent I disclose an apparatus for establishing the cranial point of orientation that is absolutely constant and from this point the accurate measuring of the human cranium and other parts of the human anatomy is made possible. A stabilizer was used in connection with the apparatus and this stabilizer was placed upon the head of the one being examined. There was no mechanical connection between the stabilizer in the patented device and the apparatus.

In the present case, the stabilizer is still mounted upon the head of the one being examined, and I provide novel means between the stabilizer and the apparatus to detect any movement of the head away from its proper position with respect to the apparatus. The novel means will instantly show any up or down movement of the head and will also show any turning of the head.

It is possible by subsequent registration to re-establish the same point of orientation of the same person. For example, a tooth impression on two "bite" models could be taken during the first examination and also an X-ray picture. Six months later, the same person could be placed in the same identical position formerly occupied and two additional "bite" models made and a second X-ray picture taken. The pictures and models for the second examination could be compared with the first to determine growth or change. The device makes it possible to reduce the number of X-ray pictures taken of a person over a period of time, and thus the detrimental effect of over exposure to the X-rays is greatly reduced.

Other objects and advantages will appear in the following specification, and the novel features of the device will be particularly pointed out in the appended claims.

My invention is illustrated in the accompanying drawings forming a part of this application, in which:

Figure 1 is a side elevation of a stabilizer used in connection with my apparatus for establishing a cranial point of orientation, the apparatus being shown in section;

Figure 2 is an end view of a portion of the stabilizer;

Figure 3 is a top plan view of the stabilizer, and the section line III—III in Fig. 1 shows that the apparatus is in horizontal cross section;

Figure 4 is an end elevation of the stabilizer and orientating apparatus illustrated in Figure 3, with one of the indicating lamps being omitted, see the arrows IV—IV in Figure 3;

Figure 5 is a section taken along the line V—V of Figure 3; and

Figure 6 is a section taken along the line VI—VI of Figure 5.

While I have shown only the preferred form of my invention, it should be understood that various changes or modifications may be made within the scope of the

2

appended claims without departing from the spirit and scope of the invention.

In carrying out my invention, I will first describe certain features of the orienting apparatus disclosed in my Patent No. 2,101,105, that are used with my improved stabilizer and then will describe the improved stabilizer in detail. The apparatus comprises a pair of boxes A and B, see Figure 3, that are movable toward and away from a median vertical plane indicated by the dot dash line C, by a mechanism, not shown. The mechanism shown in my patent for moving the boxes toward and away from each other, could be used so that the inner walls 1 and 2 of the two boxes will be disposed equal distances from the median vertical plane C, at all times.

Hinged baffles 3 are connected between the inner walls 1 and 2 of the boxes so as to prevent any light from a lamp D from passing through the space between the walls 1 and 2. In Figure 1, I show the box A provided with wheels 4 that ride on rails 5 which in turn are supported by a platform E. The box B likewise has wheels, not shown, riding on the rails 5. The lamp D is mounted in a housing F which is attached to the platform E and does not move with the boxes A and B. The housing F has two horizontally arranged slots 6 and 7, in the inner wall 8 of the lamp housing F, and these slots register with horizontal slots 9 and 10 provided in the rear walls 11 and 12, respectively, of the boxes A and B, see Figures 1 and 3. Sliding gates 13 and 14 are mounted in the boxes A and B, respectively, and are designed to be removably disposed in front of the slots 9 and 10, respectively.

There are partitions 15 and 16 arranged in the boxes A and B, respectively, and these have horizontal slots 17 and 18 that lie in the same plane as the slots 9 and 10. Additional sliding gates 19 and 20 are provided as removable closures for the slots 17 and 18, respectively. The front walls 21 and 22 for the boxes A and B, have horizontal slots 23 and 24 that lie in the same plane as the slots 17 and 18, and they register with these slots as well as the slots 9 and 10. A mirror 25 extends across both front walls 21 and 22 of the boxes A and B, and is mounted in a frame 26 that in turn is supported by the platform E so as not to be moved with the boxes A and B. The mirror has a horizontal slot 27 that registers with the front wall slots 23 and 24 of the boxes A and B.

It will also be noted from Figure 3, that the box A has aligned openings 28, 29 and 30, provided in the rear wall 11, partition 15 and front wall 21, respectively, and these openings lie in the same horizontal plane G as the slots 9, 17, 23 and 27. In like manner, the box B has aligned openings 31, 32 and 33, provided in the rear wall 12, partition 16, and front wall 22, respectively, and these openings lie in the same horizontal plane G as the slots 10, 18, 24 and 27.

The row of registering openings 28, 29 and 30, and the row of registering openings 31, 32 and 33, cooperate with the slot 27 in the mirror 25, to establish the horizontal plane indicated by the dot-dash line G in Figure 1 of the drawings. The plane G extends at right angles to the median vertical plane C. The person to be tested, looks into the mirror 25 so that the line of sight from the eyes 34 in the head H, register with the mirror slot 27. The gates 13, 14, 19 and 20 are adjusted to uncover the openings 28, 29, 31 and 32, and the boxes A and B are moved toward or away from each other until the person's eyes 34 register with the row of openings 30, 29 and 28, and the parallel row of openings 33, 32 and 31, see Figure 3.

The parts thus far described have been set forth in detail in my patent. The stabilizer now to be described and the associate mechanism, differ from the patented structure. A cap 35 is preferably placed on the person's head H and the stabilizer J is anchored to the cap so as

to be held in a fixed position on the head. The stabilizer comprises an elongated rectangular base 36, see Figures 1 and 4, that rest on a sponge base 37, and the base is kept in contact with the cap by an anchoring frame 38 which extends from opposite sides of the base 37 and connects with the hat 35. The hat is preferably tight fitting and after it is placed on the head and the stabilizer connected to the hat, a thin layer of plaster of Paris may be applied between the frame 38 and the hat for anchoring the stabilizer base from movement.

The stabilizer base 36 supports the stabilizer frame 39 by a ball and socket joint 40, see Figure 1. The frame 39 can be adjusted by adjustable legs 41 so that a platform 42 will remain in a true horizontal plane. The frame 39 rotatably supports a shaft 43 that carries a weighted wheel 44 on which markings in degrees are made. A zero marking 45, on the wheel 44, when registering with a mark 46 on the frame, will indicate that the platform 42 is perfectly horizontal in a transverse direction with respect to the longitudinal plane C.

A weighted pointer 47 is pivoted to the shaft 43 at 48 so as to always point upwardly in a vertical direction. The upper pointed end of the pointer 47, rides under a quadrant 49 that is fixed to the frame 39. When the pointer 47 registers with the center marking on the quadrant 49, the operator knows that the platform 42 lies in a horizontal plane from front to back of the platform.

Next I provide means for indicating any slight twisting of the head about a vertical axis. A superstructure frame 50, see Figures 1 and 4, has the same general length and width as the platform 42 and is disposed thereabove. Plunger type terminals 51 and 52 are carried near the ends of the superstructure frame 50 and they have wedge-shaped lower ends 53, see Figure 2, that are designed to be received in V-shaped grooves 54, provided in the upper surface of plates 55 and 56 that are mounted on top of the platform 42 and at each end thereof. The plunger type terminals 51 and 52, reciprocate in housings 50a that are carried by the superstructure frame 50. The lower ends of the housings 50a ride on the plates 55 and 56.

The grooves 54 in the plates 55 and 56 are in alignment with each other and when the vertical plane through these grooves lies parallel with the median vertical plane C, the operator knows that the stabilizer J is in proper position. As soon as the person twists his head to the right or to the left, the platform 42 will swing with the head and will move the plates 55 and 56 so that their grooves 54 will be moved out of registration with the wedge-shaped lower ends 53 of the plungers 51 and 52. The plunger type terminals 51 and 52 will therefore be raised and will close electrical circuits to lamps 57 and 58 and cause them to be illuminated, see Figure 1. The source of current and the wiring for the lamps are not shown.

A bar magnet 59 is mounted on the platform 42 and a compass 60 is carried by a housing 61 that is mounted on the superstructure 50. The bar magnet extends in the direction of the length of the platform 42. The housing 61 carries an inclined mirror 62 that reflects an image of the needle 60a of the compass, and the needle will extend in the same direction as the bar magnet 59. The compass needle permits the operator to visually note the direction in which the platform 42, extends.

Supporting means for the superstructure frame 50 is provided and this means is carried by the platform E through the mirror frame 26. The supporting means counterbalances the weight of the superstructure frame so that this weight need not be carried by the person being examined. In Figures 1, 3 and 4, I show a lever 63 that has a ball and socket connection 64 with the superstructure frame 50 for supporting it. Both Figures 3 and 4 illustrate how the lever 63 is clamped in a bracket 65 by means of a set screw 66, and Figure 5 shows the bracket carrying a shaft 67 that is rotatably mounted in an arm 68. A set screw 67' enters an annular groove in the shaft 75

67 and permits rotation of the shaft while holding it from withdrawal. The ball and socket connection 64 has a set screw 64a for securing the superstructure frame 50 from movement after the frame has been moved into the desired position.

A counterweight 69 is adjustable along the free end of the lever 63 to counterbalance the weight of the superstructure frame 50. As the person raises or lowers his head H, the superstructure frame 50 is also free to be raised or lowered because the plunger type terminals 51 and 52 will bear lightly against the plates 55 and 56. During any up or down movement of the head H, the lever 63 will cause the bracket 65 to rock on its shaft 67 disposed in the arm 68. The set screw 67' permits this rocking because it rides in the annular groove 83.

The accidental raising or lowering of the head H will be registered by a depending pointer 70, pivoted at 71 on a leg 72 that extends downwardly from the bracket 65. The leg 72 has a plurality of markings 73 arranged in an arcuate manner and the pointer 70 is free to swing and ride over these markings to indicate any movement of the lever into an angular position with respect to a horizontal plane that extends through the axis of the shaft 67. I provide means for limiting the swinging of the lever 63 and this comprises a post 74 that projects from a depending member 75 that is carried by the arm 68. The leg 72 is channel-shaped, see Figures 5 and 6, and the post 74 projects into the channel. The post 74 acts as a stop for the leg 72 and limits the swinging of the lever 63 and the leg when the post strikes either side of the channel. The pointer 70 will always extend in a vertical direction and will register any tilt of the lever on the scale 73.

The arm 68 has a leg 76 that extends at right angles to the arm and is slidably received in a sleeve 77. In Figure 4, I show the sleeve 77 as being carried by a bracket 78, which in turn is supported by the mirror frame 26. A set screw 79 secures the leg 76 in the sleeve 77. The arm 68 is extensible or contractible and is in two parts 68a and 68b. The part 68a has a tongue 79 that is slidably received in a socket 80, provided in the part 68b. The tongue and socket are both noncircular in cross section so that the part 68b will not rotate on the tongue. A set screw 81 is carried by the part 68b and secures it to the tongue 79 in adjusted position, see Figure 3.

I also provide means for detecting the forward and backward movement of the head H. An upright 85 is mounted on top of the mirror frame 26, see Figure 1, and this upright has a sleeve 86 at its top in which a beam 87 is adjustably mounted. A set screw 88 secures the beam in adjusted position. A rotatable bearing 89 is mounted near the free end of the beam, and a horizontally disposed rod 90 is adjustably mounted in the bearing and is held against longitudinal movement by a set screw 91. In Figure 4, the rod 90 is shown extending transversely of the device. In Figure 1, the rod 90 is shown extending longitudinally of the device for purposes of clarity. The bearing 89 permits the rod 90 to be swung through an arc of 360°. Markings on the two parts of the bearing permit the angular position of the rod to be noted with respect to the beam 87.

Referring to Figure 4, it will be noted that the rod 90 carries a depending rod 92 and a ball and socket 93 connect the two rods together. An X-ray film holder K is adjustably mounted on the rod 92 and set screws 93 secure the holder in the desired position. A portable level indicated by the dot dash lines in Figure 4, may be applied to the board K after the desired angle has been reached and a record kept of the particular angle of the board. This permits the board K to be brought to the exact same position at a subsequent examination of the same person. X-ray film 94 may be removably secured to the board K. In Figure 4, the X-ray film holder K is shown as being placed at one side of the head.

The description thus far has set forth a horizontal plane

G established by the eyes 34, and a vertical median plane C. The cranial point 95 of orientation, see Figure 1, is established by the intersection of these two planes plus the intersection of a transverse perpendicular plane M. The cranial point of orientation 95, established by the intersection of these three planes, is the point used for measurements to the various teeth 96. It will be noted that the plane M coincides with the glabella of the patient's head H.

A pendulum 97 is pivoted to the beam 87 at 98, and an extensible forwardly projecting arm 99 is carried by the pendulum and contacts with the patient's forehead. The point of contact between the arm 99 and the forehead, establishes the position of the transverse perpendicular plane M. The forehead is pressed against the end of the arm 99 until the pointer 100, at the top of the pendulum, registers at the zero position on the quadrant scale 101. The soft tissue in front of the glabella will be compressed so that the transverse plane M coincides as nearly as possible with the actual front portion of the skull.

It is assumed for the present case that it is desired to fix different points of the occlusal plane relative to the cranial point of orientation 95. For this purpose, the patient can make a "bite," the bite having a fixed L-shaped arm 102 extending into a receptacle 103 that is carried by the platform E, see Figure 1. The patient's head has been positioned in the manner described and the receptacle 103 can be filled with plaster of Paris 104 to hold the "bite" arm 102 in the fixed position.

The patient may now remove his head H and permit the "bite" arm to remain in position. The operator may then proceed by any suitable means to physically fix the point of orientation 95 defined by the intersection of the three planes C, G, and M, and may then take the desired measurements from this point as indicated by the line 105. Later on, the patient may place his head H in the same position formerly occupied. A second "bite" can be taken and then the operator can compare this with the first one. Growth or change can thus be detected.

It is possible to use the device when examining a person that has only one eye. When the person turns his head about a vertical axis, the lower ends of the housings 50a ride on the plates 55 and 56, while the plunger type terminals 51 and 52 move out of the grooves 54 and close the electric circuits, not shown, for illuminating the lights. Should the person raise or lower his head without twisting it, the housings 50a maintain the same spacing between the stabilizer frame 39 and the superstructure frame 50. In this way the plunger type terminals 51 and 52 will not close the electric circuits to the lights 57 when the person merely raises his head without turning it. The set screw 64a holds the super-

structure frame against relative movement with respect to the lever 63 when the stabilizer frame 39 is raised or lowered, or rotated about a vertical axis.

I claim:

- 5 1. In a device of the type described: a stabilizer adapted to be removably secured to the head of a person and including a platform; means carried by the stabilizer for indicating when the platform lies in a horizontal plane; and means for detecting when the platform swings in the horizontal plane so as to detect any turning of the person's head about a vertical axis; said last-named means including V-shaped grooves placed at the ends of the platform and being in alignment with each other; a frame supported above the platform and having depending plungers with wedge-shaped lower ends adapted to be received in the grooves; and a light carried by the frame and associated with each plunger and adapted to be illuminated when the platform is moved by the person's head for moving either or both grooves out of registry with the wedge-shaped end of the plunger; whereby the plunger will be raised and will effect the illumination of the light associated therewith.
- 10 2. In a device of the type set forth in claim 1; and in which means is provided for detecting the vertical raising or lowering of the platform caused by the raising or lowering of the person's head on which the stabilizer is mounted.
- 15 3. In a device of the type described: a platform removably secured to the head of a person; a frame disposed above the platform and having means lightly resting upon the platform; a counterbalanced lever having a ball and socket connection with the frame for supporting practically the entire weight of the frame so that the person's head will be relieved of this weight; a bracket for pivotally supporting the lever so that the lever will normally lie in a horizontal plane and will be free to swing about a horizontal axis; the bracket carrying a depending, channel-shaped leg that will swing away from a vertical position when the lever is swung; a free-swinging pointer pivotally carried by the leg; said leg having markings thereon over which the pointer swings to indicate the angular position of the lever with respect to a horizontal plane that passes through the axis of the pivotally supported bracket; and a stop received in the channel for limiting the swing of the depending leg in either direction from a vertical position.
